UNITED STATES PATENT OFFICE

2,453,051

BATHING TRUNKS

Umberto Vacca, Brooklyn, N. Y.

Application September 25, 1946, Serial No. 699,247

5 Claims. (Cl. 2—67)

1

This invention relates generally to the class of apparel and pertains particularly to improvements in bathing garments.

The present invention has for a principal object to provide means whereby the bathing trunks may be put on at home under the slacks, pants or trousers, even a skirt of the wearer and removed after the slacks, etc., have been put on so that the bather can make changes on the beach without going into a bath house or similar place and also avoiding the discomfort of having to wear the wet or damp garment home under the slacks, etc.

Another object of the invention is to provide a bathing garment of the character stated which is formed to have a back section or panel and a front section, connected by a narrow intermediate strip which is designed to position between the legs of the wearer, the back panel having side portions or wings which are designed to be brought together into overlapping relation across the front of the front section and joined to such section and to one another to effect the proper securing of the garment on the person.

Another object of the invention is to provide a garment of the character stated wherein one of the lateral or wing sections of the back panel carries a portion of a belt while a second and larger portion of the belt is carried by the back panel, with means for coupling together the two ends of the two belt sections whereby to produce a novel and attractive garment.

A still further object of the invention is to provide a bathing garment of the character stated in which the connected front and back panel sections have disposed over the inner sides thereof a shield unit of substantially hourglass form, which is shorter in length than the garment proper whereby when the garment is put on such shield unit will be caused to pull-up tightly into the crotch of the wearer so as to give effective covering protection.

Other objects and advantages of the invention will become apparent as the description of same proceeds and the invention will be best understood from a consideration of the following detailed description taken in connection with the accompanying drawings forming a part of the specification with the understanding, however, that the invention is not confined to a strict conformity with the showing of the drawings but may be changed or modified so long as such changes or modifications mark no material departure from the salient features of the invention as expressed in the appended claims.

In the drawings:

2

Figure 1 is a view in perspective of a bathing garment constructed in accordance with the present invention.

Figure 2 is a vertical section taken on a plane extending from the front to the rear of the garment as indicated by the line 2—2 of Figure 1.

Figure 3 is a view of the inside of the garment opened out.

Figure 4 is a view in front elevation of the garment in partially closed condition.

Referring now more particularly to the drawings it will be seen that the garment has a main body portion which is preferably cut from a single piece of material and is generally designated 10. This main body portion is cut or formed to provide the front and back panel sections 11 and 12 respectively, the front panel being shaped with the longitudinal or vertical curved side edges 13 to fit over or conform to the general curvature of the abdomen which it covers.

The rear panel portion 12 is of slightly greater width than the front panel portion and, as shown in Figure 3, the two portions are tapered at their adjacent and joined sides to be connected by the relatively narrow intermediate or crotch portion 14 which positions between the legs of the wearer. Thus there are formed at the two sides of the body 10 between the portions 11 and 12, the deeply incut recesses 15 which receive the legs of the wearer of the garment and which form, when closed around the wearer's legs after the application of the garment, the leg openings 16 as shown in Figures 1, 2 and 4.

The remote transverse edges of the panel portions 11 and 12 are suitably finished off to form the waist band sections 17 and 18.

As shown most clearly in Figure 3, the back panel portion 12 of the garment body is joined to, or may be formed integral with, two substantially triangular side wing portions 19. Each of these portions is secured along the base of the triangle which it defines, to a side edge of the back panel 12 along the line designated 20 while the long side edge of each triangular portion forms a continuation of the adjacent end of the waist band section 18 and is suitably reenforced by applied tape or in any other suitable manner to provide the band edge 21. Such edge of one of the triangular portions is provided with a spaced series of snap button tops 22. The waist band portion 17 which forms a part of the front panel 11 carries the button heads 23 which are received by the tops 22 when the garment is closed about the body of the wearer, in the manner hereinafter described.

The oblique edge or hypotenuse of the triangle

defined by each wing 19 extends upwardly and outwardly from the lower end of the adjacent side of the panel 12 to form a point with the side 21 of the panel so that when these wing portions are folded together one across the other and over the forward side of the panel 11, in applying the garment, they will extend upwardly across the abdomen of the wearer, the top edges 21 coming into adjacent parallel relation with the top edge of the waist band portion 17 as shown in Figures 1 and 2.

In applying the garment the body portion is positioned so that the back panel 12 can be drawn up against the back of the body and the panel 11 positioned against the front of the body or the abdomen. When so positioned the lower ends of the adjacent sides of the front and rear panels are secured together by the snap fasteners 24 and the snap button tops 22 of the left hand wing 19 are secured to the heads 23 which are carried by the front panel waist portion 17 thus securing these units together in the manner shown in Figure 4. In this figure, however, the snap button 24 at the right hand side of the garment has not been secured and the right hand wing portion 19 is shown opened.

The outer side of the edge 21 of the left hand wing portion 19 is provided with a number of snap button heads 25 with which are joined corresponding snap button tops 26 carried by the top edge portion of the right hand panel 19. In this manner the right hand triangular portion 19 is folded over the front of the left hand portion 19 giving the arrangement shown in Figure 1.

Across the front of the right hand triangular portion or wing portion 19 is fixed, in a suitable manner, a waist belt section 27 while the back panel 12 has connected therewith the longer waist belt section 28. The ends of the two waist belt sections 27 and 28 are brought together and connected by suitable separable buckles 29 as shown in Figure 1.

The waist belt sections 27 and 28 may be attached to the garment by means of the usual guide loops 30, if desired, or one or both may be permanently attached by stitching or otherwise as desired.

Upon the inner side of the body portion 10 there is secured a shield unit which is generally designated 31. This shield unit is of suitable fabric and has generally the form of an hourglass in that it has the two relatively wide end portions 32 and 33 which are joined by the long constricted intermediate portion 34, the width of which at its narrowest point is less than the width of the connecting portion 14 between the panels 11 and 12.

As shown in Figure 3 the end portions 32 and 33 are secured along their outer edges to the outer edges respectively of the panels 11 and 12 and the overall length of the shield body or unit 31 is considerably less than the overall length of the body 10 so that when the garment is applied the shield unit will be drawn up tightly into the crotch to thereby effectively cover the adjacent areas of the body.

As shown in Figure 4 the front panel 11 may be provided with a pocket which is generally designated 35. This is effectively covered by the triangular wing portions 19 when the garment is in applied position.

From the foregoing it will be readily apparent that there is provided by the present invention a novel bathing garment which may be readily removed from under the slacks, etc., without requir-

ing the bather to have to go in a bath house and similar place, and which, when applied, is firmly retained in position by the crossed wing members 19 at the front of the garment, connected one to the other and to the front panel in the manner described. These wing members in addition to giving an effective means of securing the garment in closed position, also effectively protect the garment pocket 35 in which the bather may put jewelry or other articles of value and also give effective protection to the abdomen.

I claim:

1. Bathing trunks, comprising a one piece body of material having front and back panels and a narrow connecting portion therebetween, means for joining together adjacent side edges of the panels to form a body enclosing unit, side wing portions connected to the vertical side edges of the back panel and adapted to lie one over the other across the front panel, said side wings each having an overall length substantially equal to the width of the front panel, and means for securing said portions to one another and to the front panel.

2. Bathing trunks, comprising a one piece body of material having front and back panels and a narrow connecting portion therebetween, each panel having side edges designed to be brought into adjoining relation with a corresponding side edge of the other panel, means for coupling together the adjoining panel edges, a substantially triangular wing panel joined to each of the vertical side edges of the back panel, each of said wing panels having an overall length substantially equal to the width of the front panel, the wing panels being designed to be brought into overlapping relation one with the other across the front of the front panel, means for securing said wing panels in the stated overlapping relation, and a two part waist belt having one part carried by the back panel and the other part carried by the outermost one of an overlapping wing panel.

3. Bathing trunks of the character stated in claim 2, wherein the said means for joining together the adjacent edges of the front and back panels and the overlapping panels, comprises a series of snap fasteners.

4. Bathing trunks, comprising a one piece body of material having front and back panels and a narrow connecting portion therebetween, means for joining together adjacent side edges of the panels to form a body enclosing unit, relatively long side wing portions connected to the vertical side edges of the back panel and adapted to lie one over the other across the front panel, and means for securing said portions to one another and to the front panel, each of said wing portions being of a length substantially equal to the width of the front panel, a waist belt section secured across said back panel adjacent to the top edge thereof, a waist belt section secured along one of said wing portions adjacent to the top edge thereof, and means for coupling together adjacent ends of the waist belt sections when the panels and wing portions are joined together in the manner stated.

5. A pants form of garment comprising a back panel, a front panel of approximately the same width as the back panel and a crotch portion connecting the front and back panels, a relatively long triangular member upon each side of the back panel, each member being secured along the base edge of the triangle to a side edge of the back panel with the back edge of the triangle

forming a continuation of the top edge of the back panel, said triangular members being of substantial length whereby they are adapted to be disposed one over the other across the front side of the front panel, means for attaching the triangular members to the front panel, and means for securing the triangular members one to the other.
